UNITED STATES PATENT OFFICE.

WILLIAM H. BENDER, OF CHICAGO, ILLINOIS.

LIQUID-HOLDER.

SPECIFICATION forming part of Letters Patent No. 557,352, dated March 31, 1896.

Application filed September 4, 1894. Serial No. 522,016. (No model.)

To all whom it may concern:

Be it known that I, WILLIAM H. BENDER, a citizen of the United States, residing at Chicago, in the county of Cook and State of Illinois, have invented certain new and useful Improvements in Liquid-Holders, of which the following is a full, clear, and exact description, reference being had to the accompanying drawings, and to the letters of reference marked thereon, which form part of this specification.

The object of my invention is to provide a liquid-holder so constructed and operatively arranged that it at once subserves the purposes of several bottles or the like—in other words, to provide a device arranged to contain several kinds of liquid, each of which being separated from the other may be drawn off at will in any desired order. To accomplish this object, the invention essentially embraces a subdivided bottle, flask, or the like, an adjustable or movable cap or closing-piece for the discharging end thereof, provided with a single suitable opening so disposed with reference to the motion of the closing-piece and the arrangement of the subdivisions that communication may be had with one subdivision while the other subdivisions are held securely closed, and an outlet or spout having communication by way of the said opening in said closing-piece with the interior of the bottle or flask, all of which is hereinafter fully set forth, and pointed out in the appended claim.

In the drawings, which illustrate one form of my invention, Figure 1 is a vertical section taken through the center of the liquid-holder. Fig. 2 is a horizontal section taken through the neck thereof on the line 2 2 of Fig. 1, the view being in the direction indicated by the arrows shown on said line. Fig. 3 is also a horizontal section taken through the liquid-holder on the line 3 3 of Fig. 1, the view being in the direction indicated by the vertical arrows shown on said line. Fig. 4 is an outside elevation of the closing-piece and spout shown in said Figs. 1 and 2. Fig. 5 is a bottom plan view of said closing-piece and spout. Figs. 6 and 7 are details in side elevation and bottom plan, respectively, showing the cap-piece, which I preferably employ as a bearing for the closing-piece. Fig. 8 is a detail show-

ing the nipple which secures the closing-piece in position for operation of the spout.

To fully describe the details of construction and arrangement shown in the said several views, A indicates a bottle or flask formed desirably of glass; A', subdivisions formed therein by means of integral partitions a; a', an external screw-thread formed at the upper termination of the flask; B, a metallic cap-piece fixed, by means of an internal thread b formed in its annular overlapping portion b', to the upper threaded portion a' of the flask; b², openings formed in the capping portion b³ of the part B, corresponding in number and position with the subdivisions A'; b⁴, a stem projected from the part b³, provided at its outer termination with a screw-thread b⁵, and g a flexible gasket interposed between the upper termination of the bottle or flask and the capping portion b³.

C refers to the closing-piece, movably held snugly to the cap-piece B by means of the stem b⁴ and nut and washer b⁶b⁷, respectively, (particularly shown in Fig. 1,) the stem passing through said part C through the opening c provided therein.

C' indicates the outlet or spout carried by and forming part of the closing-piece C; c', a longitudinally-movable nipple located within a suitable opening c², provided in the part c, forming connection with said outlet c', and c³ a stud or pin having a head k, projected laterally from the nipple c', working in an elongated opening or slot c⁴ in the part C. The opening c⁸, which to all intents and purposes forms part of the said outlet C', being suitably counterbored and the nipple provided near its lower end with an annular ring c⁵, a spring c⁶, desirably formed of soft rubber, is interposed between said ring and the shoulder formed by said counterbore, the spring tending to normally force the nipple in the direction of the capping-piece, the office of the nipple obviously being to stop the motion of the closing-piece when in proper position with reference to the subdivisions and make close and complete connection between the outlet C' and the openings b² in the capping portion b³.

The opening c in the closing-piece C being counterbored near its outer end, as particularly shown in Fig. 1, and a spring b⁸ being

interposed around the stem b^4 , between the shoulder formed by the counterbore and the washer located near the upper end of the stem b^4 , the closing-piece C is held firmly against 5 the cap-piece B.

The operation of the device is as follows: The nipple c' being raised by means of the pin c^3 the closing-piece is turned on the stem b^4 until the outlet C' is located immediately 10 in a desired subdivision. The pin then being freed the nipple by its lower end drops into the proper opening b^3 and the desired fluid may be drawn off, the remaining subdivisions being held closed against the escape of the 15 fluid or fluids which they contain.

It may be noted that while I have shown herewith and described herein a particular form of device I do not limit myself to the exact details of construction shown and described, as the same may be varied in many 20

particulars without deviating from the intent and scope of my invention.

I therefore claim as my invention and desire to secure by Letters Patent—

The combination of the fluid-holder A having two or more radially-arranged independent subdivisions A'; the cap-piece B fixed to the discharging end thereof provided with openings b^2 corresponding in number and order of arrangement with said subdivisions; 25 and the axially-movable closing-piece C working over the cap-piece B provided with an outlet or spout C', adapted to be positioned to discharge the contents of either one of the subdivisions, while the other subdivisions are 30 held closed; substantially as set forth.

WILLIAM H. BENDER.
